L. PAVIA

SHUTTLE

Filed Feb. 8, 1923

WITNESS

W. A. Bell

INVENTOR,
Luigi Pavia,
BY
John Edward
ATTORNEY

UNITED STATES PATENT OFFICE.

LUIGI PAVIA, OF ALLENTOWN, PENNSYLVANIA.

SHUTTLE.

Application filed February 8, 1923. Serial No. 617,821.

To all whom it may concern:

Be it known that I, LUIGI PAVIA, a subject of the King of Italy, residing at Allentown, in the county of Lehigh and State 5 of Pennsylvania, have invented certain new and useful Improvements in Shuttles, of which the following is a specification.

The object of this invention is to provide means in a loom for absorbing the 10 shock incident to the blow of the picker which impels the shuttle across the lay or batten and to the checking of the shuttle's flight at the end of the lay, whereby in particular to reduce as much as possible the 15 tendency of such shock to displace the windings of weft or filling longitudinally of the wound package. As loom shuttles are at present constructed the mass of windings, due to this shock, is frequently displaced 20 on the quill, paper tube or other core on which the windings are wound, so that it then stands loose in the shuttle.

In the accompanying drawing,

Fig. 1 is a top plan view of a fragment 25 of a shuttle embodying my invention;

Fig. 2 is a longitudinal sectional view thereof, a filling package being shown (dotted) on the spindle; and

Fig. 3 is an enlarged sectional detail view 30 taken in a longitudinal horizontal plane showing how the spindle is mounted.

a designates the body of an ordinary shuttle, *b* being its so-called quill-cavity and *c* a cavity extending therefrom and traversed 35 as usual by two pins *d* and *e* and also by two other pins *f* and *g*, the latter two affording support for a spring *h*. On the pin *d* is fulcrumed a carrier *i* which is subjected 40 to the action of the spring *h* in the manner shown in Fig. 2 so that it will be held thereby, when depressed, bearing against pin *d* and, when elevated to the dotted-line position, bearing with its butt end against the spring.

This carrier *i* is an elongated block of metal having a longitudinal hole *j* bore therethrough and formed with a counterbore *k* extending from what is its butt or rear end to nearly its opposite end; the butt end 50 of the bore is screw-threaded as indicated at *l*. There is also a slit *m* in one side of the block extending from its butt end to a point more or less forward, the same communicating with the counterbore. Into the 55 thread *l* is tapped a screw *n*.

The spindle is constructed as follows: *o*

is a spindle proper of the split type, its two legs being distended midway of their length in the usual way so that they will grip the bore of the wound package, as that 60 of the quill, paper tube or other core for the windings thereof. Over the butt end of this spindle proper is slipped a collar *p* which keeps the corresponding ends of the said legs in face to face contact with each 65 other. The collar is held against endwise displacement by a screw *q* which is tapped thereinto and bears against the spindle proper. The spindle proper has its butt end portion projecting into the hole *j* of the carrier and the collar *u* is arranged in the counterbore *k*, the head of screw *q* being arranged in the slit *m* and flattened or otherwise faceted to keep the screw from turning 70 in the collar and the spindle from turning 75 in the bore.

Between the collar and the shoulder *k'* forming an abutment at the forward end of the counterbore *k* is interposed a spiral spring *r*, and between said collar and the screw *n* forming an opposite abutment is 80 interposed another spiral spring *s*, said springs being coiled about the spindle and normally coacting to hold the spindle 85 against endwise displacement in each direction.

The carrier member, springs and parts of the spindle, with a screw *q*, may be assembled as follows: Having affixed the collar on the spindle proper by means of the screw 90 *q* and slipped spring *r* onto the spindle ahead of the collar the spindle is passed, pointed or free end first, through the carrier, the head of screw *q* being entered in slit *m*; the distended portions of the spindle 95 legs will undergo contraction in this operation, assuming their normal positions when the spindle has reached the position indicated by Fig. 3. Then spring *s* is introduced into the counterbore and finally the 100 screw *n* is driven home.

When, in use, the shuttle is subjected to any endwise shock, as that of the picker or the shuttle checking means of the loom, the inertia of the spindle is assumed by one or 105 the other of the springs, which immediately reacts to return the spindle to its normal position. Thus the shock is absorbed and so there results in practice a very much less frequent loosening or slipping of the windings of the filling package.

Having thus fully described my inven-

tion, what I claim as new and desire to secure by Letters Patent is:—

1. In combination, a shuttle body, a carrier member arranged therein and having a bore and also a slot communicating with the bore, the bore and slot extending longitudinally of the shuttle body, a spindle in said bore confined thereby to move longitudinally thereof, means in the carrier member to yieldingly oppose said movement of the spindle, and a screw screwed into and projecting laterally from the spindle and having a faceted portion in the slot confined by the latter against turning, said screw preventing the spindle from turning in the bore.
2. In combination, a shuttle body, a carrier member arranged therein and having a bore and also a slot communicating with

the bore, the bore and slot extending longitudinally of the shuttle body, a spindle in said bore confined thereby to move longitudinally thereof, said spindle including a spindle proper and a collar thereon housed in the bore, means in the carrier member and engaging said collar to yieldingly oppose said movement of the spindle, and a screw screwed into the collar against the spindle proper and securing the collar thereto, said screw projecting laterally from the collar and having a faceted portion in the slot confined by the latter against turning and said screw preventing the spindle from turning in the bore.

In testimony whereof I affix my signature.

LUIGI PAVIA.
